UNITED STATES PATENT OFFICE.

GROVER B. LANTZ, OF COLTON, CALIFORNIA.

HEAT INTERCHANGER.

Application filed July 21, 1920. Serial No. 397,930.

To all whom it may concern:

Be it known that I, GROVER B. LANTZ, a citizen of the United States, residing at Colton, in the county of San Bernardino 5 and State of California, have invented certain new and useful Improvements in Heat Interchangers, of which the following is a specification.

My invention relates to heat interchangers and its primary object is to provide a contrivance of simple and highly efficient construction which in its operation causes a rapid interchange of heat and cold between two fluid substances of different temperatures for the purpose of cooling or heating one by the influence of the other.

Another object of the invention is to expedite the heating or cooling effect upon the material under treatment by a revolving motion of a container through which it passes to a point of discharge, and still another object is to provide in apparatus of the above described character, means to prevent incrustation of the surfaces with which the material comes in contact while it is being cooled or heated.

With the above and other objects in view, all of which will fully appear in the course of the following description, my invention 30 consists of the construction, arrangement and combination of parts shown in the accompanying drawings in the various views of which like parts are similarly designated, and in which

35 Figure 1 represents a longitudinal section through my improved heat interchanger;

Figure 2, an enlarged longitudinal section of one of the end portions of the same;

40 Figure 3, a transverse section along the line 3—3, Figure 2;

Figure 4, a similar section taken on the line 4—4, Figure 2, and

45 Figure 5 a section similar to Figure 3, showing a modified construction.

Referring more specifically to the drawings the apparatus consists of a stationary vessel 2 preferably of tubular form which is supported in a substantially horizontal 50 position upon suitably constructed piers or pedestals 3.

The ends of the tubular vessel are closed by heads 4 provided with stuffing boxes 5 for the passage of axially alined gudgeons 6 and 7 at the ends of a rotary container 8 of tubular form which extends within the

vessel in spaced relation to the inner circumferential surface thereof.

The vessel has adjacent one of its ends an intake opening 9 and at the other end 60 an outlet opening 10 through which the fluid by which the contents of the container are either cooled or heated, is admitted and discharged.

The gudgeons of the tubular container 65 are fastened in plugs 12 which close the opposite ends thereof and they are supported for the rotation of the container about its longitudinal axis, in pedestal boxes 13 erected at opposite ends of the vessel in 70 which the container is disposed.

The gudgeons 7 and 6 are of tubular form to serve as conduits for the ingress and egress of material to and from the container and their ends projecting beyond the 75 bearings, are connected respectively with relatively stationary feed and discharge pipes 14 and 15 through the medium of suitable packed unions 16.

A pulley 17 mounted upon one of the two 80 gudgeons provides a medium for the rotation of the container within the vessel by connection with a conveniently located source of mechanical energy.

Rods 18 are loosely disposed in the inlet and outlet conduits of the container and the therewith alined feed and discharge pipes to prevent incrustation of the interior surfaces of the same by solids contained in the material under treatment and they are held 90 against longitudinal displacement by swivled links 19 which connect their outer ends with adjacently situated parts of the stationary pipes.

The container 8 is for the same purpose 95 provided with a number of loosely disposed objects 20 such as balls, pebbles or rods, which during rotation of the container have a grinding and scouring action upon its interior surface and thereby prevent the deposit and adhesion of incrustive matter.

Blades 21 projecting radially from the cylindrical wall of the container into the surrounding space of the cylindrical vessel are adapted to agitate the fluid by which 105 the material under treatment is cooled or heated, for the purpose of maintaining a uniform temperature.

In the operation of the machine the material to be cooled or heated is fed through 110 the pipe 14 and the conduit 7 into the container 8 and during its passage there-

through from one end to the other is subjected to the influence of a fluid of different temperature which is introduced into the vessel 2 through the intake opening 9 thereof.

The two fluids are discharged from the container and the vessel respectively through the conduit 6 and the outlet opening 10 so that subject to a continuous feed 10 the two fluids will flow constantly in opposite directions and by their contiguity interchange their temperatures to the desired degree.

The rotary motion of the container subjects every part of the material repeatedly to the heating or cooling influence of the surrounding fluid and to some extent prevents subsidence of solids in the material and subsequent incrustation of the surface 20 to which it settles.

The movements of the balls or other objects in the container and of the rods in the ingress and egress conduits of the same are, however, the principal factors in preventing the incrustation of the surfaces 25 with which the material is in contact, by their abrasive action during the revolving motion of the parts of the rotary element in which they are disposed.

30 The apparatus as hereinbefore described is suitable for either cooling or heating any fluid material, be it a liquid, solid, vapor, gas or a combination of any two or more thereof, and the medium by which the material is cooled or heated may be a liquid, 35 vapor or gas or a combination of either two or all of these fluids.

The blades on the rotary container extending into the surrounding space of the 40 vessel agitate the fluid in said space for the purpose of keeping it at a uniform temperature which especially in the use of a liquid is essential to maintain the effective influence of the fluid upon the material 45 throughout the length of the container.

By corrugating the cylindrical wall of the container as shown in Figure 5 of the drawings, incrustation thereof may be prevented to a considerable extent with or 50 without the use of balls of other abrasive objects, and I desire it understood that other changes in the construction of the parts of the apparatus may be resorted to

without departing from the spirit of my invention as defined in the hereunto appended claims.

The vessel in which the container has its movement may be made in the form of an open trough when the apparatus is used for cooling the material by the use of a liquid, the cross-sectional form of the vessel may be varied from that shown in the drawings, and the vessel may be mounted for rotation and connected with a driving element to move simultaneously with the container in 65 either the same or the opposite direction should the nature of either of the two fluids demand a movement of this kind for the operation of the machine at or near its point of maximum efficiency.

Having thus described my invention what I claim and desire to secure by Letters Patent is:

1. In a heat interchanger, a vessel adapted to receive and discharge a cooling 75 or heating fluid, a cylindrical container in said vessel having at its ends axially alined inlet- and outlet-conduits supported for its rotation, and abrasive media in said conduits.

2. In a heat interchanger, a vessel adapted to receive and discharge a cooling 85 or heating fluid, a cylindrical container in said vessel having at its ends axially alined inlet- and outlet-conduits supported for its rotation and rods loosely disposed in said conduits.

3. In apparatus of the character described, an elongate vessel adapted to receive and discharge a cooling fluid and having stuffing boxes at its ends, a tubular container in said vessel having exteriorly of its ends, axially alined, hollow, open-ended gudgeons for the admission and discharge 95 of material, separated by the space within the container, and supported in the boxes for rotation of the same, relatively stationary inlet and outlet pipes in fluid-tight connection with the gudgeons, an abrasive medium loose in the container to prevent by the rotary movement thereof incrustation of its inner surface, and means for the 100 rotation of the container.

In testimony whereof I have affixed my signature.

GROVER B. LANTZ.
